The Schedule referred to in these Letters Patent and making part of the same.

TO ALL WHOM IT MAY CONCERN:

Be it known that I, JOSEPH SCHOLFIELD, of the township of Constantine, county of St. Joseph, State of Michigan, have originated and designed a new Pattern for a Trade-Mark or brand for such goods as I may manufacture. It consists of a representation of a roll of cloth, partially unrolled, in which one of the selvedges is of a different color from the cloth and from the other selvedge, as represented in the accompanying drawing.

What I claim as my invention, and desire to secure by Letters Patent, is—

The design for a trade-mark or brand, as shown and described.

JOSEPH SCHOLFIELD.
